MANUALLY AND AUTOMATICALLY ADJUSTABLE CHOKE FOR SHOTGUNS

Arne Y. Grahn, Hartford, Conn., assignor to The Poly Choke Company, Incorporated, East Hartford, Conn., a corporation of Connecticut

Application September 17, 1957, Serial No. 684,583

10 Claims. (Cl. 42—79)

This invention relates to a choke mechanism for firearms and especially shotguns, and relates more particularly to an automatically adjustable choke mechanism in which the adjustment of the choke is effected by the firing or discharge of the gun. The choke is also manually adjustable.

Adjustable choke mechanisms for firearms have long been known and automatically adjustable choke mechanisms have been proposed, such mechanisms usually comprising a split or slotted choke tube which is attached to the gun barrel, and a relatively movable sleeve surrounding the choke tube and adapted to constrict it when moved upon the tube. Usually the arrangement is such that the constricting sleeve is moved in some manner in response to the firing of the gun so that automatic adjustment of the amount or degree of choke is effected.

An automatically adjustable choke mechanism has a distinct advantage over a manually adjustable type in that very often a hunter will be able to get more than one shot at game after it has been flushed, that is, the hunter will be able to fire more rapidly owing to the automatic adjustment of the choke mechanism. Usually the first shot is made when the game is relatively close and no choking action or relatively little choking action is required. On the next shot the game is usually at a greater distance from the gun and a closer pattern of shot is, therefore, desirable. The same is true if a third shot can be fired before the game is out of range. If these successively closer patterns may be effected by the choke mechanism in response to the firing of the gun more shots may be obtained at game where it would not be possible to adjust the choke manually between the consecutive discharges of the firearm without the game getting out of range.

As previously stated, adjustable choke mechanisms usually comprise a slotted or constrictable tube and a relatively movable outer sleeve to effect restriction of the tube. However, in the present instance an effective choking action is obtained by means of an inexpensive choke tube which is of constant diameter, that is to say, that the cylindrical wall of the tube is not interrupted by slots. Furthermore, the tube, in the present instance, is of substantially uniform diameter except adjacent its rear end where it receives the charge of shot from the muzzle of the gun barrel. The diameter of the choke tube is substantially that of the gun barrel, and choking action is obtained by varying the distance of this tube from the nozzle of the barrel.

For example, it has been found that when the rear end of the choke tube is close to the muzzle of the gun barrel a substantially open pattern is effected, that is to say, almost the same pattern which might be obtained without the use of any choke mechanism. However, when the choke tube is advanced a certain extent, say a half inch, away from the muzzle of the gun barrel a degree of choking action is obtained, while, if the choke tube is moved so that its rear end is, for example, substantially an inch from the muzzle of the gun barrel, a

substantially full choking effect is obtained. By making use of this principle and by providing a choke tube of constant bore which may be moved forwardly by discharge of the gun, and which is releasably held in various adjusted positions so that it moves forwardly in a step-by-step manner, one step at each discharge of the gun, a reliable and efficient automatically adjustable choking mechanism is obtained by, in effect, lengthening the gun barrel.

10 One object of the invention is to provide an improved automatically adjustable choke mechanism which very effectively chokes a shotgun and which is very reliable in operation.

15 A further object is to provide an automatically adjustable choke mechanism in which the choke tube is rotated to an extent each time the firearm is discharged, the tube being rotated in first one direction and then the other.

20 Still another object of the invention is to provide a choke mechanism having improved means for releasably holding the choke tube in various adjusted positions so that it moves forwardly in a step-by-step manner, and in which means is also provided for manually locking the tube in various adjusted positions.

25 Another object is to provide releasable holding means for the choke tube which acts directly on the tube.

Further objects of the invention will be apparent from the following detailed description of one form of the choke mechanism illustrated in the accompanying drawings by way of example.

In the drawings:

Fig. 1 is a side elevational view of the muzzle of a gun barrel having a choke embodying the invention applied thereto;

35 Fig. 2 is an enlarged sectional view on line 2—2 of Fig. 1 showing the choke in open-bore position;

Fig. 3 is a view similar to Fig. 2 showing the parts in an intermediate choke position;

Fig. 4 is a view similar to Fig. 3 but showing the parts 40 in full-choke position;

Fig. 5 is a sectional view taken on line 5—5 of Fig. 2;

Fig. 6 is a sectional view taken on line 6—6 of Fig. 2; and

Fig. 7 is a fragmentary view illustrating a development 45 of the choke tube.

To illustrate an embodiment of the invention there is shown in the drawings the muzzle of a gun barrel 10 having secured thereto by brazing, or equivalent means, an adapter 11. Adjacent the forward end thereof the 50 adapter 11 is provided with external screw threads for mounting a cylindrical member 12 having internal threads at the rear end thereof so that it may be threadedly secured to the adapter.

As shown in Fig. 2, the internal diameter of the cylindrical member 12 is somewhat greater than the bore 13 of the gun barrel and the member 12 is provided with an internal annular recess 14 adjoining and forwardly of the last-mentioned threads of the member. Adjacent the forward end thereof the cylindrical member 12 is provided with a rearwardly facing shoulder 15 formed by internally recessing, as at 16, the bore of the member 12, this recess being of annular form and providing a forwardly facing shoulder, as at 17. As shown in the last-mentioned view, the forwardly facing shoulder 17 is formed by an abrupt edge of the recess 16 while the rearwardly facing shoulder 15 is formed by a beveled and forwardly sloping edge of the recess. A tubular choke member 18 is slidably mounted within the member 12 and the wall of the choke member is continuous circumferentially in that it is not provided with longitudinal slots as is usually the case in adjustable choke mechanisms. Therefore, the tubular member is of constant diameter in the sense that

its diameter is not changed at any point by constriction or expansion during use of the choke mechanism. Moreover, the diameter of the tubular member over the greater portion of its length is substantially the same as that of the bore 13 of the gun barrel. At the rear or entrance of the choke member 18, however, the inner wall is flared, as at 19, so as to provide a funnel-shaped portion to receive the charge of shot from the muzzle of the gun barrel. It will be appreciated that as the rear of the choke member 18 may be slightly spaced forwardly a distance of $\frac{1}{32}$ of an inch or more from the muzzle of the gun barrel in the position of Fig. 2, the charge of shot may expand slightly before it reaches the member 18. The flared portion 19 of the choke member collects the shot and directs it into the portion of the member which is of substantially the same diameter as the bore 13 of the gun barrel.

A split ring 20 embraces the choke member 18 and extends into the internal annular recess 16 formed in the cylindrical member 12, the width of the ring being substantially that of the recess. The ring 20 is held against appreciable movement in the recess by contact of its abrupt rear edge with the abrupt forwardly facing shoulder 17, and by contact of the rearwardly facing and beveled shoulder 15 cooperating with the forward and beveled edge 21 of the ring. The split ring 20 fits, with a suitable amount of friction, about the outside diameter of the tubular member 18 and, as the ring is held against axial movement within the cylindrical member 12, it inhibits relative movement between the latter and the choke member. When the choke member 18 is moved forwardly by the discharge of the gun, as will appear hereinafter, there is a tendency for the ring 20 to move forwardly and contact the beveled surface 15 of the cylindrical member 12, and this contact tends to constrict the ring about the choke member so as to exert the required friction upon the latter. It will be manifest that it is desirable not to have the choke member moved throughout its full choking range by a single discharge of the gun, but to have it move in a step-by-step manner and to this end a locking means is provided to releasably hold the choke member at various positions of adjustment axially of the gun barrel as will appear hereinafter.

An outer cylindrical or sleeve member 23 embraces the cylindrical member 12, the member 23 having a cylindrical side wall structure providing clearance with the cylindrical side wall structure of the member 12. As shown in Fig. 2, the sleeve member 23 is shorter than the cylindrical member 12 and at its outer end is provided with an inwardly extending circumferential flange 24, the flange being threadedly secured to external threads formed at the forward end of the tubular choke member 18. Thus it will be understood that the tubular choke member is, in effect, integral with the outer sleeve member 23 and in its movements carries the member 23 with it. Hence the members 18 and 23, when secured together, may be referred to as the choke tube.

To releasably hold the choke tube in positions of adjustment axially of the gun barrel either the choke tube or the cylindrical member 12 is provided with a fixed stop member. In the form illustrated in the drawings, the stop member, indicated at 25, is provided on the cylindrical member 12 and cooperates with a track which, in this instance, is formed, not on the sleeve member 23 as it might be, but on the tubular choke member 18, the track being indicated at 26. As shown in Fig. 2, the fixed stop member 25 is formed by a radially inwardly extending headed pin at the forward extremity of the cylindrical member 12 and received in the side wall structure thereof. The track 26 is generally of zigzag or V shape (see Fig. 2), the arms thereof being curved outwardly somewhat from the apex of the V. In the instant form the track 26 is formed by grooving the external surface of the tubular member 18. The grooved

track 26 is provided with extensions 28, 29 for a purpose which will appear hereinafter.

The automatic operation of the choke mechanism is as follows. When the parts of the choke mechanism are in the open-bore position of Fig. 2 and the stop pin 25 is located in the track in the broken-line (see Fig. 7) position indicated at 30, subsequent discharge of the gun effects movement of the stop pin 25 relatively to the choke tube so that the pin travels along the track 26 until stopped by the latter in the broken-line position 31 shown in the last-mentioned view. This movement is effected by the outward propulsion of the choke tube, probably due to the impact of the shot as it is gathered in the collection portion 19 of the tube. It will be understood that during this movement of the choke tube the tube is rotated to some extent due to the direction of the track 26. It will also be understood that the split ring 20 serves to frictionally restrain the outward movement of the choke tube. Due at least in part to the momentum of the rotary movement of the choke tube the stop pin 25 travels down one arm of the V-shaped track but does not travel along the other arm of the track until the gun is discharged a second time. It will be understood that when the stop pin 25 comes to rest in the last-mentioned position the choke tube is in the intermediate position of Fig. 3 and subsequent discharge of the gun effects further movement of the stop pin 25 relatively to the track 26 so that the pin 25 travels along said other arm of the V-shaped track 26 coming to rest in the broken-line position (see Fig. 7) indicated at 32. As the pin travels along the track 26 to the last-mentioned position thereof, the choke tube is rotated in the other direction. A third shot may be fired in this position of the choke parts and it will be understood that when the parts are in this, the full-choke, position (Fig. 4) further choking action is prevented by engagement of the stop pin 25 with the inner terminal of the track 26. Thus it will be understood that the choke tube is moved from the open-bore position of Fig. 2 to the full-choke position of Fig. 4 in a step-by-step manner and it will be further understood that, if desired, additional outward adjustments of the choke tube may be effected by providing a longer zigzag track for the stop pin 25 instead of a V-shaped track. As shown in Fig. 4, the outer surface of the cylindrical member 12 may be provided with indicia cooperating with the rear edge of sleeve 23 to give a visual indication of the degree of choke.

The choke tube may be manually adjusted and may be locked in either the open-bore or intermediate choke positions. This may be done by manipulation of the sleeve member 23. For example, when the stop pin 25 is in the open-bore position 30 indicated in Fig. 7, the sleeve member 23 may be grasped and rotated to move the pin 25 relatively to the choke tube so that the pin enters and engages in the extension 28 of the track. When the stop pin 25 is in the last-mentioned position, the choke tube is effectively held against axial movement when the gun is subsequently fired. When the choke mechanism is in the open-bore position rearward movement of the choke tube is prevented by engagement of the flange 24 with the front end of the cylindrical member 12. When it is desired to lock the pin 25 in the intermediate choke position, the choke tube may be rotated to move the pin 25 relatively to the choke tube so that the pin moves from the position 31 shown in Fig. 7 to a position in the extension 29 of the track. It will be understood that when the pin 25 is engaged in the extension 29 subsequent discharge of the gun does not effect outward movement of the choke tube. As shown in Fig. 7, the extension 29 is slightly offset from the center of the V-shaped groove 26, the extension being offset in a direction to inhibit entrance of the pin into the extension 29 as the choke mechanism is set for automatic adjustment, that is, when the pin 25 is in the position 30, indicated in Fig. 7, prior to discharge of the gun.

It will be further understood that the choking effect of the mechanism in any given position thereof will vary in accordance with the diameter of the tubular member 18, and that while the member 18 is indicated in the drawings to be of substantially the same diameter as the bore 13 of the gun barrel, the internal diameter of the tubular member 18 at the forward end thereof may be somewhat greater or less than the diameter of the bore 13, if desired.

One advantage of the choke mechanism resides in the provision of the pin and track means constituting the releasable lock for holding the choke tube in its automatically adjusted positions. The pin and track means reduces friction in the releasable lock to a minimum. Furthermore, there is provided means for preventing automatic adjustment of the choke tube and for locking the latter manually in various adjusted positions. It will be appreciated that in the form shown the releasable locking means for holding the choke tube in either its manually or automatically adjusted positions is interposed between the fixed cylindrical member and the inner choke member, the locking means acting directly on the latter. Still further, it will be understood that owing to the provision of the track on the outer surface of the inner choke member the entrance of dirt or other foreign matter into the track is effectively inhibited. In this connection it may be noted that the outer sleeve member 23 extends over all portions of the track, as shown in Fig. 4. It will be manifest from the foregoing disclosure that there is provided an improved choke mechanism constituted by few and simple parts and which is very reliable in operation.

While only one form of the choke mechanism has been shown in the drawings and described above, it will be apparent that the choke mechanism may take other forms and is susceptible of various changes in details without departing from the principles of the invention and the scope of the appended claims.

What I claim is:

1. A choke mechanism for a gun barrel comprising a hollow cylindrical member extending forwardly from the muzzle of the gun barrel in fixed relation thereto, a choke member comprising a tubular charge-choking element extending into and slidably in said cylindrical member for forward propulsion by impact on said element of a charge fired from the gun, and cooperating interengaging means on said members for effecting a step-by-step forward movement of the tubular element on discharge of the gun, said means comprising a zigzag track on one of the members cooperating with a stop element fixed to the other member and relatively movable along the track, so that the choke member is rotated in first one direction and then the other as it is advanced.

2. A choke mechanism for a gun barrel comprising a hollow cylindrical member extending forwardly from the muzzle of the gun barrel in fixed relation thereto, a choke member comprising a charge-choking tubular element extending into and forwardly slidable in said member, for forward propulsion by impact on said element of a charge fired from the gun, the choke member having a sleeve element embracing the cylindrical member and rigid with the tubular element at the forward end of the latter so as to be slidable therewith, one of said elements having a zigzag track formed thereon and facing the cylindrical member, said cylindrical member having a stop pin fixed thereto and relatively movable along the track, so that the tubular element is rotated in first one direction and then the other as it is advanced, for effecting a step-by-step movement of the tubular element on discharge of the gun.

3. A choke mechanism for a gun barrel comprising a fixed element having a tubular part extending forwardly from the muzzle of the gun barrel, a choke tube having a first and charge-choking tubular part extend-

ing into and forwardly slidable in said part of the fixed element, for forward propulsion by impact thereon of a charge fired from the gun, said choke tube having a second tubular part embracing said part of the fixed element and rigid with said first tubular part at the forward end of the latter so as to be slidable therewith, and cooperating interengaging means between one of said tubular parts of the choke tube and said tubular part of the fixed element, for effecting a step-by-step forward movement of the choke tube on discharge of the gun, said means comprising a stop element fixed on one of the two last-mentioned tubular parts and a zigzag track on the other, the stop element being relatively movable along the track so that the choke tube is rotated in first one direction and then the other as it is advanced.

4. A choke mechanism for a gun barrel comprising a fixed member having a cylindrical part extending forwardly from the muzzle of the gun barrel, a choke tube having a charge-choking tubular part extending into and forwardly slidable in the cylindrical part, for forward propulsion by impact on said tubular part of a charge fired from the gun, and cooperating interengaging means on said member and choke tube to restrain forward movement of the tubular part and to rotate the latter first in one direction and then the other so that the tubular part is advanced in a step-by-step manner.

5. A choke mechanism for a gun barrel comprising a fixed member having a cylindrical part extending forwardly from the muzzle of the gun barrel, a choke tube having a charge-choking tubular part extending into and forwardly slidable in the cylindrical part, for forward propulsion by impact on said tubular part of a charge fired from the gun, and cooperating interengaging means on said member and choke tube to restrain forward movement of the tubular part and to rotate the latter first in one direction and then the other so that the tubular part is advanced in a step-by-step manner, said means acting directly on said tubular part.

6. A choke mechanism for a gun barrel comprising a fixed member having a cylindrical part extending forwardly from the muzzle of the gun barrel, a choke tube having a charge-choking tubular part extending into and forwardly slidable in the cylindrical part, for forward propulsion by impact on said tubular part of a charge fired from the gun, and cooperating interengaging means on said member and choke tube to restrain forward movement of the tubular part and to rotate the latter first in one direction and then the other so that the tubular part is advanced in a step-by-step manner, said means acting directly on said tubular part and comprising a V-shaped track on one of said parts cooperating with a stop pin fixed to the other part.

7. A choke mechanism as defined by claim 6, wherein said means includes a split ring carried by one of the parts and bearing against the other to restrain forward movement of the tubular part.

8. A choke mechanism as defined in claim 7, wherein at the distal end of the forward arm of the V the track is provided with an offset extension so that the stop pin may be manually locked therein to prevent forward propulsion of the tubular part on discharge of the gun, the track being provided with a second pin-locking extension adjacent the apex of the V-shaped track.

9. A choke mechanism as defined by claim 8, wherein the track is formed by a groove in the outer cylindrical surface of the tubular part and the stop pin is fixed to and extends radially inwardly from the cylindrical part, the choke tube having a second tubular part of a length to extend over the track and embracing the cylindrical part in fixed relation to the first tubular part.

10. A choke mechanism comprising a cylindrical member adapted to be secured to the muzzle of a gun barrel, a choke tube comprising a charge-choking tubular member extending into and forwardly slidable in the cylindrical member, for forward propulsion by impact on

said tubular member of a charge fired from the gun, the choke tube having a sleeve member embracing the cylindrical member and rigid with the forward end of the tubular member so as to be carried thereby, and cooperating interengaging means on the cylindrical member and the choke tube providing various positions in which the choke tube may be manually and selectively locked against propulsion by discharge of the gun, and also providing for self-propulsion of the tube

through a rotary movement of the latter in a step-by-step manner.
